JOHN F. O'CONNOR, OF CHICAGO, ILLINOIS, ASSIGNOR TO W. H. MINER COMPANY, OF CHICAGO, ILLINOIS, A CORPORATION OF ILLINOIS.

RAILWAY PASSENGER-CAR DRAFT-RIGGING.

No. 829,730.

Specification of Letters Patent.

Patented Aug. 28, 1908.

Application filed March 29, 1906. Serial No. 308,653.

To all whom it may concern:

Be it known that I, JOHN F. O'CONNOR, a citizen of the United States, residing in Chicago, in the county of Cook and State of Illinois, have invented a new and useful Improvement in Railway Passenger-Car Draft-Rigging, of which the following is a specification.

My invention relates to improvements in draft-rigging for railway passenger-cars, and more particularly to improvements in construction of the side plates or stop-castings of railway draft-rigging for passenger-cars. As is well known, the side plates or stop-castings of railway draft-rigging are subjected in practical use to enormous blows, shocks, or strains, and heretofore great difficulty has been experienced from the draft-rigging breaking or giving away at the side plates or stop-castings or at the shoulders thereon against which the followers abut. Heretofore draft-rigging side plates or stop-castings have always been made of plates or webs of unequal thickness at different points, and especially at the intersection of the stop-shoulders with the main plate or web of the stop-casting, and I have observed that the breakage is most apt to occur apparently at these intersections or points where the metal is thicker.

The object of my invention is to provide a passenger-car railway draft-rigging side plate or stop-casting of a simple, strong, efficient, safe, and reliable construction and capable of successfully withstanding the enormous shocks or blows to which the draft-rigging is subjected in actual and practical use.

My invention consists in the means I employ to practically accomplish this object or result—that is to say, it consists of a railway passenger-car draft-rigging side plate or stop-casting, made, as usual, of malleable iron or other annealed metal and provided with the customary stops or shoulders for the followers to abut against, and which is composed throughout of a web of uniform thickness, both at the stops or shoulders, as well as elsewhere, so that the stop-casting as a whole will be entirely free from T or other sections, which would result in giving the casting a greater thickness or body of metal at some points than others, with the consequent imperfections, casting strains, and defects which have heretofore been incident to the

making of side plates or stop-castings of the old construction wherein the stops or shoulders form right angle or T sections with the main plate or web of the casting, and in which the main web of the side plate or stop-casting is provided with a horizontal or longitudinal bend or convolution at its upper edge adapted to fit against the upright web of the passenger-car center sill and project between the upper and lower flanges of the center sill, and in which the upright bends or convolutions of the main web of the stop-casting terminate at this upper longitudinal bend or convolution.

In practicing my invention the stop-shoulders are formed on the side plate or stop-casting by integral convolutions in the main web of the side plate or stop-casting, the convolutions or bends forming the stop-shoulders being upright and the web of the casting being of substantially uniform thickness at these stop convolutions or bends as well as elsewhere, and in practicing my invention the horizontal or longitudinally-extending strengthening ribs or flanges likewise consist of integral bends or convolutions in the main web of the casting without producing any T-sections or thickened parts therein to produce defects and strains or other weaknesses in the casting operation.

My invention also consists in the novel construction of parts and devices and in the novel combinations of parts and devices herein shown and described.

By my invention I am enabled to produce not only a much safer and stronger stop-casting and draft-rigging than those heretofore in use, but I am also enabled to manufacture the stop-castings very much cheaper, as by my invention scarcely any defective castings are produced, whereas in making the stop-castings heretofore in use there has always been a heavy percentage of castings that on test have to be rejected and broken up as unfit for use.

In the accompanying drawings, forming a part of this specification, Figure 1 is a side elevation, partly in longitudinal vertical section, of a draft-rigging embodying my invention. Fig. 2 is a vertical cross-section on line 2 2 of Fig. 1. Fig. 3 is a detail top or plan view of one of the side plates or stop-castings. Figs. 4 and 5 are detail vertical sections on lines 4 4 and 5 5, respectively of

Fig. 3; and Fig. 6 is a detail longitudinal section on line 6 6 of Fig. 2 of one of the stop-castings.

In the drawings, A represents the center sills, A' the cross-sill, A² the carry-iron, B the draw-bar, C C the springs, and D the followers, of a railway passenger-car draft-rigging, these parts being of any ordinary or suitable construction.

- 10 F F are the side plates or stop-castings, each being composed of a cast-metal web F' of uniform thickness throughout, and each having on their inner side a plurality of stops or shoulders f for the followers to abut 15 against, and also a plurality of intermediate stops or shoulders f' to limit the compression of the springs, all these stops or shoulders being formed by integral upright convolutions or bends F² in the main web F' of the side 20 plate or stop-casting, so that the casting as a whole will have no T-sections or increased thickness at the points where the stops or shoulders join or intersect the main web of the casting. The side plate or stop-casting 25 F is further provided with an upper integral longitudinal or horizontal bend or convolution F³ on its outer side, which fits against the upright web a of the center sill A and between the lower flange a' and upper flange a² of the 30 center sill, this upper longitudinal bend or convolution F³ forming longitudinal strengthening ribs or flanges f² f³. Each of the side plates or stop-castings F is also furnished near its lower edge with a longitudinal 35 bend or convolution F⁴, forming strengthening ribs or flanges f⁴ f⁵. The upright or stop-forming bends or convolutions F² terminate short of and do not extend across the upper horizontal web or convolution F³.
- 40 My improved passenger-car side plate or stop-casting is thus composed of a cast web of substantially uniform thickness throughout, while at the same time having the necessary upright stop-shoulders, and also furnished with an integral upper longitudinal bend or convolution to fit against the upright web of the metal center sill.
- 45 I claim—

- 50 1. In a draft-rigging for railway passenger-cars, the combination with the draw-bar, springs and followers, of side plates or stop-castings, each consisting of a cast web of substantially uniform thickness throughout, having an integral upper longitudinal convolution 55 therein adapted to fit against and be secured to the upright web of the center sill, and furnished also with a plurality of upright convolutions forming stops or shoulders for the followers to abut against, substantially as specified.
- 60 2. In a draft-rigging for railway passenger-cars, the combination with the draw-bar, springs and followers, of side plates or stop-

castings, each consisting of a cast web of substantially uniform thickness throughout, 65 having an integral upper longitudinal convolution therein adapted to fit against and be secured to the upright web of the center sill, and furnished also with a plurality of upright convolutions forming stops or shoulders for 70 the followers to abut against, said cast web having also a longitudinal convolution at its lower part, substantially as specified.

3. In a draft-rigging for railway passenger-cars, the combination with the draw-bar, 75 springs and followers, of side plates or stop-castings, each consisting of a cast web of substantially uniform thickness throughout, having an integral upper longitudinal convolution therein adapted to fit against and be secured to the upright web of the center sill, and furnished also with a plurality of upright convolutions forming stops or shoulders for 80 the followers to abut against, said upright convolutions terminating below said upper 85 longitudinal convolution, substantially as specified.

4. The railway passenger-car draft-rigging side plate or stop-casting, consisting of a cast web of substantially uniform thickness 90 having upright convolutions therein forming stops or shoulders for the followers to abut against, and an upper longitudinal convolution to fit against the car-sill, substantially as specified.

5. The railway passenger-car draft-rigging side plate or stop-casting, consisting of a cast web of substantially uniform thickness having upright convolutions therein forming stops or shoulders for the followers to abut against, 100 and an upper longitudinal convolution to fit against the car-sill, said upright convolutions being below said upper longitudinal convolution, substantially as specified.

6. The railway passenger-car draft-rigging 105 side plate or stop-casting, consisting of a cast web of substantially uniform thickness having upright convolutions therein forming stops or shoulders for the followers to abut against, and an upper longitudinal convolution to fit against the car-sill, said web having also at its lower portion a longitudinal convolution, substantially as specified.

7. The railway passenger-car draft-rigging 115 side plate or stop-casting, consisting of a cast web of substantially uniform thickness, having upper and lower longitudinal or horizontal convolutions, and provided with upright convolutions extending below the upper longitudinal convolution and forming stops or shoulders for the followers to abut against, 120 substantially as specified.

JOHN F. O'CONNOR.
